US0D1016949S

(12) **United States Design Patent** (10) **Patent No.:** **US D1,016,949 S**
(45) **Date of Patent:** **** Mar. 5, 2024**

(54) **ADJUSTABLE CLIMBING WALL**

(71) Applicant: **Everlast Climbing Industries, Inc.**, Minneapolis, MN (US)

(72) Inventors: **Timothy Shawn Sudeith**, Edina, MN (US); **Sarah Mae Howard**, Lakeville, MN (US); **Benjamin Tiffin**, Missoula, MT (US); **Joel Greenblatt**, Wauwatosa, WI (US); **Joseph Sweeney**, Minneapolis, MN (US); **Aaron Jon Baumgartner**, Savage, MN (US); **Justin Lee**, Eagan, MN (US)

(73) Assignee: **EVERLAST CLIMBING INDUSTRIES, INC.**, Minneapolis, MN (US)

(**) Term: **15 Years**

(21) Appl. No.: **29/833,571**

(22) Filed: **Apr. 5, 2022**

(57) **CLAIM**

The ornamental design for an adjustable climbing wall, as shown and described.

DESCRIPTION

FIG. 1 is a front perspective view of an adjustable climbing wall showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The broken lines in the drawings illustrate portions of the adjustable climbing wall that form no part of the claimed design.

1 Claim, 5 Drawing Sheets
